SPLIT FEED "DUO-SOL" OPERATION

Fred L. Fast, Sewell, and Harold Button, Pitman, N. J., assignors to Secony Mobil Oil Company, Inc., a corporation of New York

Application July 25, 1952, Serial No. 300,864

4 Claims. (Cl. 196—14.2)

The present invention relates to the separation of mixtures of hydrocarbons into fractions which are more paraffinic than the charge stock and into fractions more aromatic than the charge stock in which two substantially immiscible solvents are used and the charge is extracted with one solvent in an operation in which at least some part of the extraction with the one solvent takes place in the presence of the other solvent. Such an operation is known as the "Duo-Sol" process. The present invention relates to an improved method of operating a "Duo-Sol" unit to obtain an increased yield of raffinate without increasing substantially the total amount of solvents and without changing substantially the ratio of one solvent to the other.

The "Duo-Sol" process has been described in various publications notably U. S. Patent No. 1,912,348 (May 30, 1933) and Reissue No. 19,763 (1,912,349; May 30, 1933) granted to Malcolm H. Tuttle and in *Petroleum Refiner*, vol. 26, No. 4 "Process Handbook Section," page 138. As described in the latter publication: "The basic principle of the 'Duo-Sol' process is the simultaneous use of two practically immiscible solvents in an extractor system having one or more extract stripping stages in addition to the conventional raffinate stripping stages. Propane is employed as a paraffinic solvent and 'Selecto' a blend of phenol and cresol, is the selective naphthenic solvent, separation of the two layers in each extraction stage is accomplished by gravity."

The Selecto layer takes into solution the asphaltic unstable and otherwise undesirable fractions of the charge stock. The propane layer carries the stable paraffinic lubricating fractions. The two solvents flow counter-currently through the extractor system, the charge stock being introduced at an intermediate stage. As is shown in the flowsheet, the extract layer is contacted with an increasingly concentrated propane solution in flowing from stage 3 to stage 1, and is thereby stripped of any paraffinic fractions it might contain. In a similar manner, as the propane-raffinate layer flows in the opposite direction from stage 3 to stage 7, it comes into contact with a more and more concentrated solution of "Selecto," thus being stripped of its asphaltic oil content.

Solvent recovery from each layer is accomplished by vaporization of propane in a high pressure tower and the stripping of "Selecto" from each layer in a low pressure tower.

While a detailed flowsheet is provided on page 139 of the aforesaid publication for use in conjunction with the description provided therein, a less detailed and more diagrammatic flowsheet will suffice those skilled in the art for an understanding of the present invention. Such a simplified flowsheet is given in Figure III of the drawings.

As pointed out in the Tuttle patents, a characteristic of a lubricating oil which distinguishes the Pennsylvania lubricating oils from the mixed base Mid-Continent and/or the naphthenic or asphaltic base lubricating oils from the Gulf Coast and California is a difference in the

viscosity-gravity constant. Consequently, it has become common practice to use the viscosity-gravity constant (V. G. C.) as a means of determining the quality of a lubricating oil and as a control means in plant operation.

With the increased demands for high grade lubricants, and the decrease in available materials of construction coupled with rising costs of construction, it has been necessary to find some means of increasing the capacity of units such as "Duo-Sol" units without additions to existing plant facilities which according to widespread opinion among theoreticians and practical men were operating at full capacity. It was surprising therefore to discover that a "Duo-Sol" plant which was handling its full capacity of charge stock was capable of handling up to 75 and even 100% more of a suitably prepared secondary feed in addition to the full complement of regular primary feed without increasing substantially the total amount of solvent and without changing substantially the ratio of one solvent to the other.

Accordingly, it is an object of the present invention to provide a method of operating a "Duo-Sol" unit to increase the yield of raffinate of required quality without changing substantially the basic solvent ratios, the total amount of solvents used for extraction per unit time, and

without enlarging the extraction unit. It is another object of the present invention to modify the operation of a "Duo-Sol" extraction unit operating on a charge of feed comprising a long residuum and producing a lubricating oil fraction having a required viscosity-gravity constant

(V. G. C.) to increase the yield of lubricating oil fraction without substantial change of total solvent used and the ratio of one solvent to the other by simultaneously treating in addition to said long residuum an amount of at least partially deasphalted oil equivalent to up to 100% of the long residuum. It is a further object of the present invention to treat substantially simultaneously a long residuum in amount equivalent to the full rated capacity of a "Duo-Sol" unit and a fraction

of mineral oil of the same or different crude, said fraction adjoining said long residuum in end point of boiling range which has been deasphalted to at least some extent either by distillation or solvent deasphalting, in amount up to 100% of said long residuum without enlarging the extraction capacity of the extraction section of said "Duo-Sol" unit to obtain a lubricating fraction of required viscosity-gravity constant. Other objects and advantages will become apparent to those skilled in

the art from the following discussion taken in conjunction with the drawings in which: Figure I is illustrative of the relation, distillation-wise, of the several fractions of crude oil; Figure II is illustrative of the relation of primary feed to secondary feed; Figure III is a flowsheet in a more or less diagrammatic manner of the extraction section of a "Duo-Sol" unit.

Broadly speaking, the present invention provides a method of increasing the output of raffinate of required quality from a two solvent extraction system having an extract end and a raffinate end in which the solvent for paraffinic hydrocarbons is introduced near the extract end, the solvent for non-paraffinic hydrocarbons is introduced near the raffinate end, and the primary feed is introduced at a point intermediate the center of the system and the extract end by introducing a secondary feed into the system at a point intermediate the raffinate end and the point at which the primary feed is introduced into the system. Preferably the primary feed is introduced into the system at a point about midway of the extract end and the midpoint of the system, while the secondary feed is introduced at the midpoint of the system.

65

70

Turning to Figure I, the relation of the various fractions into which crude petroleum is divided in the initial stages of refining become apparent. A crude which has been subjected to distillation to a temperature of about 600° F. is a topped crude and represents a mixture of those components of the original crude boiling above the gas oil range. From the topped crude can be removed the lower boiling lubricating fractions known as the distillates and bright stock. The mixture of components of the crude boiling above the end point of the wax distillates are known as "long residuum." By subjecting the long residuum to distillation under vacuum, a lubricating fraction can be recovered which subjected to further refining yields lubricating oil.

When desired, the long residuum, or long resid, can be solvent deasphalting and refined or the long resid can be subjected to the refining action of the "Duo-Sol" process without deasphalting by either distillation or solvent deasphalting. Furthermore, a long resid can be partially deasphalting by solvent deasphalting and a partially deasphalting oil having a Conradson Carbon Residue of about 4 to about 6 weight per cent obtained and this in turn further refined by the "Duo-Sol" process.

The present improved method of operating a "Duo-Sol" unit provides for treating an undeaasphalting long resid and a fraction adjoining it simultaneously in a "Duo-Sol" unit the total volume of the two feed stocks being substantially greater, up to 100%, then the rated capacity of the "Duo-Sol" unit for the long resid.

By "fraction adjacent" is meant, a fraction of topped crude having an end point approximating or somewhat higher than the initial boiling point of a short residuum, or short resid. Thus, such a fraction is quite similar to a long resid or a short resid in that a major portion if not all of the constituents thereof are of the same molecular weight and chemical constitution as the non-asphaltic portion of a long or short resid.

Thus, considering Figure II a long resid contains paraffinic hydrocarbons P, non-paraffinic hydrocarbons N, and asphaltic materials A. In the "Duo-Sol" process the paraffinic hydrocarbons are removed as a propane solution known as the raffinate while the non-paraffinic hydrocarbons N and asphaltic materials A are removed as a "Selecto" solution thereof known as the extract. The long resid containing paraffinic hydrocarbons, non-paraffinic hydrocarbons and asphaltic material is a primary feed to a "Duo-Sol" unit.

The secondary feed can be either an adjoining fraction 1, having an end boiling point substantially the same or somewhat higher than the initial boiling point of a short resid, a partially deasphalting long resid 2, an adjoining fraction 3 or a partially deasphalting fraction 4. It will be noted that all of these secondary feeds have a characteristic common to each of them and to the primary feed, i. e., they all contain constituents of substantially the same molecular weight and have a distribution of paraffinic and non-paraffinic hydrocarbons similar to that of the primary feed.

The use as secondary feeds of fractions such as adjoining fraction 1, adjoining fraction 3, partially deasphalting fraction 4 and deasphalting long resid is not to be confused with the use as a secondary feed of a fraction containing little if any constituents having a molecular weight corresponding to that of the preponderant portion of the hydrocarbons in a long resid, i. e., the hydrocarbons as distinct from the asphaltic materials.

Thus, for example, a wax distillate boiling below 500° F. at 10 mm. Hg was dewaxed and the dewaxed oil redistilled under a vacuum to give an overhead cracking stock and a bottoms. The physical characteristics of both a dewaxed neutral and a bright stock obtained by redistillation of a small portion of a "Duo-Sol" "Split Feed" raffinate, produced from a commercial "Duo-Sol" operation employing two parts by volume of a residuum

and one part by volume of a distillate having a viscosity of 43 S. U. S. at 210° F., are presented below:

	Duo-Sol Raffinate	Redistillation of Duo-Sol Raffinate

The viscosity index data show that when "Duo-Sol" refining such a mixture of distillate bottoms and resid there is a tendency to over-refine the distillate bottoms and under-refine the resid.

The data presented in Tables I and II show that similar quality products, based on viscosity index, can be prepared by either blending a "Duo-Sol" refined bright stock and a conventionally acid-refined neutral or by "Duo-Sol" refining the same materials by the split-feed technique wherein the charge to the "Duo-Sol" was composed of two parts by volume of residuum and one part by volume of a distillate having a viscosity of 43 S. U. S. at 210° F.

	V. G. C.		

The data presented in Table III further establishes the fact that in the "split-feed" operation of a "Duo-Sol" unit of commercial size the effect upon the raffinate produced, based on viscosity index, is comparable to that obtained when blending a "Duo-Sol" treated bright stock and a conventionally refined neutral. The data below are typical of "Duo-Sol" operations when employing the split-feed technique and using a distillate having a viscosity of 44.6 70 S. U. S. @ 210° F. for the secondary charge stock.

TABLE III

	Average No. 50 gal. bbls. Charged/ day	Av. Grav.	Treated Oil				Tar		
			Av. Grav.	Av. Vis. @210°	Av. V. G. C.	Av. yield bbls. per day	Percent yield	Av. bbls. per day	Percent yield
Resid 36½	2,871	18.05	29.1	85.6	0.7999	1,631	54.6	1,354	45.4
Split-Feed: Resid 36½	2,211	21.9	28.4	65.0	0.8111	2,576	75.1	852	24.9
Distillate 910	1,153	26.4							

Assuming the primary feed, resid 36½, in the split-feed operation were refined to the same extent as when refined as the sole feed, then from 2211 barrels about 1000 barrels of tar would be recovered. However, only 852 barrels of tar were obtained.

It was previously established that the use of a distillate with a final boiling point in the order of 500° F. @ 10 mm. of Hg resulted in a tendency to over-refine the neutral and under-refine the residual fraction. In addition, on the basis of the following data and computations it is manifest that the split-feed operation, as in Table III, makes it possible to obtain additional refined oil from the primary residuum charged to the unit. This incremental oil which is of lower viscosity index (see Table III) may be used because of the increase in viscosity index due to blending the neutral and bright stock within the "Duo-Sol" extraction system. When the 36½ stock was refined alone the treated oil had a viscosity of 85.6 seconds at 210° F. When the 36½ stock and 910 stock were refined in the split-feed operation, the treated oil had a viscosity of 65.0 seconds @ 210° F. Whereas, had the same quantity of 910 stock (see Table III) been "Duo-Sol" refined alone in the normal manner, about 960 barrels of the same viscosity index raffinate with a viscosity of 44 seconds @ 210° F. would be produced. "Duo-Sol" refining of the 2211 barrels of 36½ stock in the normal manner would have resulted in production of about 1210 barrels of the same viscosity index (98) bright stock as indicated in Table III having a viscosity of 85.6 seconds at 210° F. Thus, from "Duo-Sol" refining the neutral and residuum individually in blocked operations, 2130 barrels of oil would have been produced having a blended viscosity index of about 100 and a viscosity, based on blending charts, of 60 at 210° F. However, in the split-feed operation 2576 barrels of a 65.0 S. U. V. @ 210° F., 98 viscosity index oil, were obtained. It is thus manifest that 446 barrels of additional oil were obtained by utilizing split-feed "Duo-Sol" operations. From blending charts this recorded oil has a viscosity of 105 at 210° F. and a calculated viscosity index of about 92. Thus, it is established that a stock in which the major constituents have a molecular weight of a different order compared to the molecular weight of the major portion of the paraffinic constituents of a resid, results in sub-standard refining of the raffinate obtained from the resid, but increases the yield and viscosity of the raffinate therefrom. Consequently, to obtain the same severity of refining on the resid fraction when split-feeding a 910 stock or similar neutral stocks as obtained when "Duo-Sol" refining the resid alone, increased refining severity, attended by a probable sacrifice in resid raffinate productions, would be required. However, when a fraction having a major portion of its constituents of the same order of molecular weight and comparable or increased paraffinicity as the preponderant portion of the paraffinic constituents of the primary feed is used as a secondary feed in split-feed operation of a "Duo-Sol" unit, the primary effect is a refining of the secondary feed to the same level as the primary feed without a decrease in the capacity of the "Duo-Sol" unit to refine the primary feed. This is demonstrated by a comparison of data obtained in the customary operation of a "Duo-Sol" unit in which the sole feed is a resid (PT 36½) with data obtained in split-

feed operation of a "Duo-Sol" unit with the aforesaid resid as the primary feed and a heavy distillate, designated as Hy16, as the secondary feed. Data for customary operation are presented in Table IV, and data for split-feed operation are given in Table V.

Those skilled in the art will recognize that both raffinates are of equal quality as determined by V. G. C. and V. I. Those skilled in the art will also note that the yield of raffinate from the split-feed operation exceed that from the usual mode of operation by about 6% on a yield of 2215 barrels of raffinate per day. When this increase in yield of raffinate is obtained for a year's operation of say 300 days at a throughput of say about 4000 barrels per day, the increased yield is about 44,500 barrels of raffinate per year. Furthermore, it will be noted that such an increase is based upon the use of secondary feed to the extent of only about 10 volume per cent of the primary feed whereas the present invention includes the use of secondary feed to equal up to 90% of the primary feed.

Similarly, a residuum designated as PHF-356, was treated in the usual manner as the sole feed to a "Duo-Sol" unit and subsequently was treated as a primary feed with an overhead cylinder stock, designated Hy16, as a secondary feed. The data obtained in these comparative runs are presented in Table VII. Another comparative run between a residuum, designated Hy-36½ as a sole feed and one in which the same resid (Hy-36½) was the primary feed and the overhead cylinder stock Hy16 was the secondary feed was made. The data for this comparison are given in Table VIII.

15 It is manifest that, although the oil to solvent ratio based upon the amount of residuum charged in split-feed operation was the same as that based upon total charge in normal operation, about 10 volume per cent more charge as a secondary feed was treated with an increase yield of raffinate of substantially the same quality in both tests.

20 Another residuum, Aramco 36½, and a Hy16 stock were treated as primary and secondary feeds with the results given in Table IX. Equilibrium conditions were established on a P and T 36½ residuum at a feed to propane ratio of 3.03 the primary and secondary feed was treated at a charge to propane ratio of 3.11 (based on the weight of primary feed charged). The secondary feed represented about 23% of the primary feed. The raffinate was obtained in 53.3 volume per cent yield and had the following characteristics:

Gravity, A. P. I. °	27.2
Viscosity, sec., S. U. V. @ 210° F.	76.3
V. G. C.	0.8155

45 Illustrative of the fact that solvent deasphalting as well as distillation deasphalting fractions of mineral oil containing an appreciable portion of constituents of said fraction having molecular weights of the same order as the major portion of the non-asphaltic constituents of the primary feed to a "Duo-Sol" unit may be used as a secondary feed to said "Duo-Sol" unit is the data given in Table 50 IX of a "Duo-Sol" operation employing the present novel split-feed technique. The secondary feed was a solvent deasphalting fraction of a Kuwait crude having the following boiling range and gravity:

Specific gravity	0.9357
I. B. P. ° F.	1490
5% ° F.	784
10% ° F.	922
20% ° F.	947
30% ° F.	960
40% ° F.	2975

60 55 1 Corrected to 760 mm.

60 60 2 Began to crack.

70 75 The solvent deasphalting oil was charged to compartment 5 while the primary feed was charged to compartment 3 of a "Duo-Sol" unit having 9 cells or compartments. Both the control run and the "split-feed" runs were made with the same solvent ratios based upon the amount of residuum charged (by weight).

Having demonstrated the unobvious results obtained by 75 the novel split-feed operation of a "Duo-Sol" unit, i. e.,

A further modification included in the basic concept is illustrated by run No. 2 of Table X wherein a propane deasphalting resid and an overhead cylinder stock were introduced into compartment No. 5 as secondary feed, crude resid was introduced into compartment No. 3 as primary feed and the "Selecto" and propane introduced into the unit as in run No. 1. The crude resid, the propane deasphalting resid, and the blend of propane deasphalting resid and overhead cylinder stock yielded the following inspection data:

charging to a compartment or cell of a "Duo-Sol" unit intermediate the cell into which the resid to be treated is introduced and the cell into which the solvent for non-paraffinic hydrocarbons is introduced, the novel split-feed operation will be discussed in sufficient detail in conjunction with Figure III for those skilled in the art to understand the modus operandi.

Let us assume that a "Duo-Sol" unit is being operated on a given residuum at full capacity to produce a raffinate of given quality. The required results are then 10 being produced under conditions of a given resid-solvent for non-paraffinic hydrocarbons-solvent for paraffinic hydrocarbons ratio by weight. (In the following discussion the solvent for non-paraffinic hydrocarbons will be considered to be "Selecto" a mixture of about 65% to about 20% phenol and the balance mixed cresols and the solvent for paraffinic hydrocarbons will be considered to be propane.) Without changing the resid-"Selecto"-propane ratio a secondary feed comprising an at least partially deasphalted fraction of mineral oil sufficiently close to said resid to have a specific gravity of not less than about 90% of that of the resid being treated is introduced into a cell intermediate the cell into which the resid is introduced and the cell into which the "Selecto" is introduced. The secondary feed is introduced into the unit without an appreciable increase in the amount of "Selecto" or propane being charged to the unit since the object, briefly stated, is to increase the output of raffinate of required quality from the unit without increasing the amount of solvent in circulation. Other operating factors and operating conditions are maintained substantially the same as they were before introduction of the secondary feed.

Assuming that the resid to be treated has not been treated previously in the unit. Generally, previous laboratory tests have established the probable optimum conditions for treatment. Consequently, there is no difficulty for those skilled in the operation of a "Duo-Sol" unit to translate the laboratory results into refinery practice.

While at the present time it is preferred to introduce the primary feed into the #3 cell of the unit and to introduce the secondary feed into the #5 cell of the unit, in general the secondary feed can be introduced into any one or all of the cells 4, 5, 6 and 7. In the event that the unit is a 7-cell unit with the primary feed introduced into the #3 cell, the secondary feed can be introduced into either the #4 or the #5 cell, or into both. In other words, it is preferred to introduce the secondary feed into the middle cells of the unit.

A conventional "Duo-Sol" 9 cell unit is represented, without auxiliary equipment such as pumps, heat exchangers, solvent separating and recovery systems etc., in Figure III. The cells are numbered consecutively beginning with the cell 1 into which the propane is introduced through pipe 11 and from which the extract ("Selecto" solution or suspension of asphaltic material and other undesirable constituents of the feed) is discharged through pipe 12. "Selecto" is introduced through line 29 into the last cell (#9 to Fig. III) from which the raffinate (propane solution of refined oil) is discharged through pipe 30. The primary feed, i. e., resid is introduced into cell #3 through pipe 13 where the feed encounters the two solvents, is thoroughly mixed therewith and settled into two phases, a propane-oil phase and a "Selecto"-asphalt phase by gravity. Mixing and settling occurs in each cell, the propane solution of treated oil flowing counter-current to a leaner and leaner "Selecto" stream as the refined oil passes from cell to cell to the discharge cell #9. The propane solution of refined oil passes from cell #1 to cell #9 through pipes 14, 15, 16, 17, 18, 19 and 20 while the "Selecto" extract passes from cell #9 to cell #1 through pipes 21, 22, 23, 24, 25, 26, 27 and 28. Secondary feed is introduced into one or more of the middle cells of the unit such as cell #5 through line 31, contacts and is mixed

with the propane solution from cell #5 and the extract solution from cell #6 and each fraction of the secondary feed is then subjected to contact with leaner and leaner "Selecto" solution or leaner and leaner propane solution respectively as the refined oil travels with the refined oil of the primary feed to cell #9 and the "Selecto" extract of the primary feed travel to cell #1. The refined oil is then further treated as required such as by percolation and dewaxing.

The secondary feed can be any fraction of the same or different crude which has a preponderant portion of hydrocarbons having a molecular weight of the same order as the non-asphaltic constituents of the resid. The secondary feed can be completely deasphalted or partially deasphalted. Thus, referring to Fig. I the primary feed can be a long resid having an initial boiling point of at least about 300° F. at 10 mm. of mercury or a short resid having an initial boiling point at least of about 500° F. to 550° F. at 10 mm. of mercury. With either resid as a primary feed, a fraction having an initial boiling point of at least 300° F. and of substantially reduced asphalt content can be used as a secondary feed. The secondary feed can have an asphaltic content sufficient to yield a Conradson Carbon Residue of about 0.1 to about 2.5 to about 3 wt. per cent. Another means of characterizing a suitable secondary feed is to say that it has a specific gravity at least about 90% of that of the resid to be treated as a primary feed. The fractions 1, 2, 3, 4, 5 and similar fractions diagrammatically indicated in Figure II, deasphalted or partially deasphalted either by distillation or solvent deasphalting or similar fractions which are obtained from crudes containing little or no asphalt can be treated as secondary feeds. However, fractions such as diagrammatically indicated at 6 of Figure II 30 whether from asphaltic base or non-asphaltic base crudes cannot be treated and the refining effect obtained thereon.

From the foregoing discussion of the modus operandi of, and the results obtained from, the present novel split-feed operation of a "Duo-Sol" extraction unit it is manifest 40 that the present invention comprises introducing a primary feed into a compartment of a "Duo-Sol" unit intermediate the point of introduction of the solvent for paraffinic hydrocarbons and the middle compartment of the extraction unit introducing a secondary feed into at least one compartment intermediate the point of introduction of said primary feed and the cell into which the solvent for non-paraffinic hydrocarbons is introduced and treating the primary and secondary feed with amounts of solvent for paraffinic hydrocarbons and solvent for non-paraffinic hydrocarbons in substantially the same proportion and in substantially the same amount as required to treat the amount of primary feed being treated in a unit of time to produce a raffinate of the required quality.

We claim:

55 1. In the art of refining mineral oil in which an oil comprising paraffinic and non-paraffinic constituents as a primary feed is extracted in a plurality of stages providing for countercurrent passage therethrough of a solvent and an added liquid adapted to form a two-liquid solvent system with a solvent having greater solvent power for non-paraffinic than for paraffinic constituents introduced into the final stage in the presence of an added liquid having greater solvent power for paraffinic than for non-paraffinic constituents introduced into the initial stage and in which an extract phase is withdrawn from said initial stage and a raffinate phase is withdrawn from the final stage, the improvement which comprises introducing said primary feed into a stage intermediate the initial stage and the mid-point of said plurality of stages, selecting a secondary feed consisting of an at least partially deasphalted oil, other than said primary feed, having a specific gravity not less than 90 per cent of the specific gravity of said primary feed, having a preponderant portion of the hydrocarbons thereof in the same molecular weight range 60 as that of the non-asphaltic constituents of said primary

13

feed and having a distribution of paraffinic and non-paraffinic hydrocarbons similar to that of the primary feed, whilst introducing said primary feed at a maximum rate concomitant with maximum yield of a raffinate of required quality, introducing said secondary feed into at least one stage intermediate the stage into which said primary feed is introduced and the final stage of said plurality of stages, and without increasing substantially the amount of said solvent or said added liquid but with an amount of said solvent and said added liquid sufficient to produce phase separation in the stage into which said primary feed is introduced, treating said primary feed and said secondary feed simultaneously to produce an increased yield of raffinate of substantially the same quality as produced when treating said primary feed.

2. The improvement of claim 1 wherein the primary feed is selected from the group consisting of long and short residua.

14

3. The improvement of claim 1 wherein the primary feed is selected from the group consisting of long and short residua, the primary feed is introduced into the stage midway the initial stage and the mid-point of said plurality of stages, and the secondary feed is introduced into the stage at the mid-point of said plurality of stages.

4. The improvement of claim 1 wherein the primary feed is selected from the group consisting of long and short residua and the secondary feed adjoins the end boiling point of said primary feed.
